UNITED STATES PATENT OFFICE.

WALTER H. TIBBALS, OF SYRACUSE, NEW YORK.

HAND FIRE EXTINGUISHER.

1,425,297.

Specification of Letters Patent.

Patented Aug. 8, 1922.

Application filed December 17, 1913. Serial No. 807,222.

To all whom it may concern:

Be it known that I, WALTER H. TIBBALS, of Syracuse, in the county of Onondaga, in the State of New York, have invented new and useful Improvements in Hand Fire Extinguishers, of which the following, taken in connection with the accompanying drawings, is a full, clear, and exact description.

10 This invention relates to certain improvements in hand fire extinguishers of the class set forth in my Patent No. 1,214,971, issued February 6, 1917, and refers more particularly to means for preventing the entrance of air into the tube in any position of adjustment of the container until practically all or at least a predetermined quantity of the fire-extinguishing liquid has been discharged.

20 The device shown is highly effective in discharging practically all of the liquid contents while the container is held in an upright position or sufficiently so to cause the liquid to cover the lower open end of the tube during the discharge, but I have discovered that if the container is inverted so as to expose the lower end of the tube in the air space, the device will simply discharge air and not liquid which is objectionable particularly in the hands of careless or unskilled operators.

30 The primary object, therefore, of my present invention is to enable the device to discharge practically its entire contents of liquid in any position either upright, inverted or at different angles from a horizontal or vertical position and at the same time to maintain a liquid seal at the valve seat and also at the joint between the valve case and

40 bushing.

Other objects and uses relating to specific parts of the device will be brought out in the following description.

In the drawings—

45 The figure is a longitudinal vertical sectional view, partly in elevation, of a hand fire extinguisher, embodying the various features of my invention.

50 As illustrated the fire extinguisher comprises a cylindrical container —1— having end heads —2— and —3— secured to the cylindrical shell to form air- and water-tight joints, the end head —3— being provided with a central opening in which is secured a bushing —4— firmly held in place by a jam

nut —5— and sealed by solder or equivalent means to form a liquid- and air-tight joint.

The bushing —4— is provided with a central cylindrical opening in which is permanently secured a tube —6— and a reduced 60 threaded end of a valve case —7—, the latter being secured in place and sealed against leakage, the outer end of the tube being also soldered or otherwise hermetically sealed in the bushing against leakage of air or liquid. 65

The valve case is provided with a main passage —9— and a branch passage —10—, the main passage communicating with the interior of the container —1— through the tube —6— which extends from the head 70 —3— to the point near the head —2— while the branch passage —10— communicates with a valve chamber —11— and terminates in a discharge nozzle —12— which is adapted to be connected to a pump or to an air 75 compressor or equivalent device for forcing air through the passages —10— and —9— and thence through the tube —6— into the interior of the container for compressing the liquid and maintaining it under a sufficient 80 pressure above the atmosphere to expel practically all of the liquid contents.

The passage —9— terminates in a valve seat —13— opening into the valve chamber —11— and is normally engaged by a needle 85 valve —14— to close the passage —9—.

The valve —14— is provided with an enlarged threaded portion —15— engaged in an opening in the valve case just at the outside of the valve chamber, the outer portion 90 or stem of the valve being cylindrical and is extended through a gland or stuffing box —16— and provided with a hand-piece or wheel —17— by which the valve may be opened and closed. 95

A washer of any suitable material is interposed between the packing of the gland and adjacent outer end of the threaded portion —15— to compress or tighten the packing on the stem when the valve is opened 100 so as to more effectively pack the joint against leakage. The valve is coaxial with the tube and closes against the pressure.

The means for automatically regulating the amount of liquid which may be introduced into the container —1— and which also serves as an air vent to permit the escape of air during the introduction of such liquid, consists of a relatively small tube —19— having one end permanently secured 110

by brazing, soldering or otherwise to the inner end of the bushing —4— at one side of and in close proximity to the tube —6— to communicate with the vent passage —20— 5 leading from the tube —19— through the outer end face of the bushing so that when the valve case —7— is removed for filling the container with the fire-extinguishing liquid, the air may escape freely from the 10 container out through the tube —19— and passage —20— to the atmosphere, but when the valve case is replaced in the bushing and tightened, the lead gasket covers the mouth of the passage —20— and effectively prevents any possibility of escape of air or 15 liquid from the interior of the container.

The opposite or inner end of the vent tube —19— extends beyond the required level of the liquid and is returned toward the top, 20 and terminates some distance from the head —3— to automatically regulate the amount of liquid which may be introduced into the container by establishing a liquid seal at the mouth thereof and preventing further escape 25 of the air.

The return bend, as —21—, of the inner end of the tube —19— serves to trap the liquid which may enter therein through its upturned end, thereby preventing the escape 30 of air through said tube as soon as the liquid reaches a level sufficient to overflow into the tube.

It is, therefore, evident that as soon as the vent is cut off by the liquid seal in the return 35 bend of the tube —19—, the air will be trapped in the air chamber of the container —1— and thus prevent the entrance of additional liquid which will simply overflow at the outer end of the tube leaving the 40 container filled with liquid to the level of the upturned end of the trap of the tube —19—.

This automatic regulation of the volume 45 of the liquid obviates the use of any gage and assures the introduction of an exact predetermined quantity of liquid in all receptacles.

When the required amount of fire-extinguishing liquid is introduced into the container, the valve case —7— is firmly screwed 50 in operative position and the valve —14— opened whereupon the pump or other air compressor may be attached to the nozzle —12— for introducing air under any desired pressure into the interior of the container 55 through the passages —10— and —9— and tube —6—. After the container is charged in the manner described, the valve —14— may be opened for an instant just sufficient 60 to allow the escape of air from the tube and passage —9— or until the liquid fills said tube and passage to establish a liquid seal at the valve seat when the valve is again and finally closed thus forming also a liquid seal 65 at the joint between the valve case and bushing —4— of the container.

In order to further reduce the liability of leakage, the entire interior surface of the container is coated with wax or equivalent coating capable of being evenly distributed to render the walls of the container im- 70 pervious to air or liquid.

The means for preventing the entrance of air from the interior of the container into the tube —6— and thereby permitting the discharge of practically all of the liquid contents of the container in any position in which the device might be held preferably 75 consists of an auxiliary U-shaped tube —35— having both arms running parallel with the main tube —6— to points in proximity to 80 opposite ends of the container —1— and one arm journaled in the main tube —6— to rotate therein so that if the container is brought to a substantially horizontal position, the other arm of the tube —35— will 85 swing to the lower side of the container to assure the immersion of its end in the liquid until a predetermined quantity has been discharged from the container, thereby preventing 90 the entrance of air into the main tube during such discharge.

The U-shaped auxiliary tube —35— has one leg inserted through the inner or lower end of the main tube —6— and upwardly to a point in proximity to the upper container 95 head where it is rounded to form a valve —36— coating with a corresponding spherical valve seat —37— for closing connection between the main tube and delivery passage —9— in the valve case —7—. 100

The other leg of the auxiliary tube —35— extends from a point near the lower head —2— of the container to a point near the opposite head —3— and in close proximity to the side wall of the container parallel 105 with the main tube —6—.

The leg of the auxiliary tube —35— which extends through the main tube —6— is of somewhat less diameter than the interior diameter of the main tube and is loosely 110 mounted therein so as to permit the auxiliary tube to turn freely about the axis of the main tube by its own weight as the container is tilted or turned about its axis, thereby assuring the positioning of the outer 115 leg of the auxiliary tube at the lower side of the container in case the latter is tilted to approximately a horizontal position which assures a liquid seal for the open end of the auxiliary tube when the container is in 120 such position until practically all of the liquid is discharged from the container.

What I claim is:

1. In a fire extinguisher of the class described, a receptacle containing a fire extinguishing liquid and air under abnormal pressure and having a passage in one end serving as an inlet for compressed air and an outlet for the liquid, a valve for said passage, a main tube leading from the passage 130

into the receptacle, and an auxiliary tube having means for cutting off communication between the main tube and said passage when the inner end of said main tube is exposed to the air in the receptacle.

- 5 2. In a fire extinguisher of the class described, a receptacle containing a fire extinguishing fluid and having a delivery passage, a main tube extending from said 10 passage into the interior of the receptacle, an auxiliary tube having a portion thereof movable endwise in the main tube and provided with a valve controlling communication between the main tube and passage, and 15 a separate valve for controlling the escape of liquid through said passage.

3. In a fire extinguisher of the class described, a receptacle having a delivery pas-

sage in one end and a valve therefor, a main tube leading from said passage into the receptacle, an auxiliary tube having a portion thereof extending into the main tube and turnable therein and another portion extending along the outside of the main tube, said auxiliary tube having an independent endwise movement and provided with a valve for alternately closing and opening communication between the main tube and passage as the receptacle is reversed end for end.

In witness whereof I have hereunto set my hand this 6th day of December, 1913.

WALTER H. TIBBALS.
